FABRIC TAKE-UP DEVICE FOR FLAT WARP
KNITTING MACHINES

Emil Herbert Wirth, Hartmannsdorf, near Chemnitz, Germany, assignor to the firma Emil Wirth Wirkmaschinenfabrik, Hartmannsdorf, near Chemnitz, Germany

Application July 29, 1937, Serial No. 156,409
In Germany August 4, 1936

4 Claims. (Cl. 66—149)

The present invention relates to flat warp knitting machines and more particularly refers to a mechanism driven by an endless chain, rope, cord or the like for winding the fabric into a roll in flat warp knitting machines.

According to the U. S. Patent 2,064,710 granted to applicant, the chain or the like is passed over a sprocket wheel or cable drum associated with the take-up roller and over a sprocket wheel or cable drum actuated by a ratchet wheel to maintain a substantially constant length of chain or the like between said sprocket wheels and the roller on which the fabric is wound is driven by a separate and automatically regulatable mechanism. In the chain or the like a tension roller is suspended which is loaded by a take-up weight.

In dependence on the constantly increasing take-up tension during knitting, the weight must be altered to obtain as uniform a tension of the chain as possible and thereby to warrant an always uniform strength of the fabric. This manner of taking-up the fabric under the influence of the load on the chain requires a constant control of the fabric take-up device.

The object of the present invention is to provide a device for taking-up the fabric by means of which the disadvantages of the known devices of this kind are avoided. In an extremely simple manner and independently on the attention of the operator the new device warrants an absolutely uniform strength of the fabric to be taken-up and thereby prevents the formation of striped goods.

The object aimed at according to the invention is substantially obtained by the fact, that the roller, freely suspended in the drive chain or the like, is connected to a fixed bearing member for a spindle, driven by the ratchet gear of the fabric take-up device, by means of a spring and a strap screwed on the spindle and prevented from rotating.

In the accompanying drawing one construction according to the invention is shown by way of example.

In this drawing:

Fig. 1 is a broken away more or less diagrammatic side view of the essential parts of a fabric take-up device of the kind shown in the above mentioned U. S. Patent 2,064,710 modified in accordance with the invention, and

Fig. 2 shows an elevation of this device.

The chain 29 or the like influencing the fabric take-up device is, as shown in the U. S. Patent 2,064,710 granted to applicant, guided over sprocket wheels 8 and 11 and a roller 17 provided

with a flange on each side. The sprocket wheel 8 is fixed upon the shaft 6 and the roller 17 is mounted upon the shaft 16. Differing from the construction shown in the above mentioned patent the sprocket wheel 11 in the present case is 5 mounted upon a hollow shaft 5 in which a solid shaft 7 is arranged carrying a sprocket wheel 53. The latter is connected by an endless chain 54 with a second sprocket wheel 75 of the same 10 diameter as the sprocket 53. According to the invention the sprocket wheel 75 is fixed upon a shaft 56 which carries a worm 58 engaging a worm wheel 57. The shaft 56 is journaled in a frame 59 pivotally connected by a bolt 60 to a bearing member 62 fixed to the machine frame. 15 The bolt 60 passes through the free end of a prong 61 of said bearing member 62. A pawl 65 pivoted to a second prong 63 of the bearing member 62 is provided with a recess 66 which engages over a pin 67 fixed to the frame 59, whereby the 20 frame 59 usually is held in operative position in which the worm 58 engages the worm wheel 57.

According to the invention, a tension spring 69 is connected to the roller 30, freely suspended in the chain 29, by means of a strap 68. A second strap 70 is suspended at the lower end of the tension spring 69. The strap 70 is provided with a female thread cooperating with the thread 71 of a spindle 72 carrying the worm wheel 57. A projection 73 of the strap 70 has a recess adapted 30 to slide on a guide pin 74 fixed in the prongs 61 and 63, of the bearing member 62 so that rotation of the strap 70 is prevented. Consequently 35 on turning the spindle 71, 72 the strap 70 and the projection 73 are adjusted in a vertical plane, whereby the spring 69 is more or less tensioned, that is to say, the chain 29 is more or less loaded.

As by way of the endless chain drive 53, 54, 75 the spindle 71, 72 is rotated by the ratchet gear influencing the take-up device and as, moreover, said spindle is connected to the drive chain 29 for the fabric take-up device by a tensioned spring 69, automatically adapting itself to any alterations, the chain 29 is always tensioned in accordance with the fabric take-up, so that, even 40 with extremely fast running machines, the formation of stripes in the fabric, due to an irregular load of the chain 29, is prevented.

If, after finishing the take-up of the fabric, the strap 70 is to be returned to its exit position 50 for the purpose of initially tensioning the spring 69, i. e. if the strap 70 is to be shifted downwardly, the pawl 65 is disengaged and the frame 59, carrying the shaft 56, is swung around the bolt 60, so that the spindle 71, 72 and the worm wheel 57 55

fixed upon the latter may be freely rotated in its bearings provided in the prongs 61, 63 by means of a hand wheel 76 mounted upon the spindle 72. As soon as the frame 59 is swung into operative position again and the worm 58 is brought into engagement with the worm wheel 57, shifting of the strap 70 with respect to the spindle 71, 72 and thereby an alteration of the tension of the spring 69 is prevented, until the shaft 56, carrying the worm 58, is again rotated by the ratchet gear, thereby rotating the spindle 71, 72.

What I claim is:

1. In a fabric take-up device for flat warp knitting machines of the kind set forth, a chain driving the fabric take-up device and carrying a freely suspended roller, a bearing member fixed to the machine frame, a spindle journalled in said bearing member, means for rotating said spindle by the ratchet mechanism influencing the fabric take-up device, and means for resiliently connecting said spindle to said freely suspended roller.

2. In a fabric take-up device for flat warp knitting machines of the kind set forth, a chain driving the fabric take-up device and carrying a freely suspended roller, a bearing member fixed to the machine frame, a spindle journalled in said bearing member, a worm wheel mounted on said spindle, a frame pivoted to said bearing member, a

shaft journalled in said frame, a worm mounted on said shaft and engaging said worm wheel, a sprocket wheel fixed on said shaft, a second sprocket wheel of equal diameter driven by the ratchet mechanism influencing the take-up device, an endless chain connecting said sprocket wheels, a threaded strap screwed on said spindle and prevented from rotating, a second strap fixed to said freely suspended roller, and a spring connected to said straps.

3. A fabric take-up device for flat warp knitting machines of the kind set forth in claim 2 in which said frame carrying said shaft is pivoted by a bolt to a prong of said bearing member and usually is held in operative position by a pawl pivoted to a second prong of said bearing member.

4. A fabric take-up device for flat warp knitting machines as set forth in claim 2 in which said frame carrying said shaft is pivoted by a bolt to a prong of said bearing member and usually is held in operative position by a pawl pivoted to a second prong of said bearing member, and in which said threaded strap is provided with a projection guided on a rod fixed in said prongs of said bearing member.

EMIL HERBERT WIRTH.
